UNITED STATES PATENT OFFICE.

GEORGE J. HULBERT, OF SEATTLE, WASHINGTON.

ADJUSTABLE SAW.

1,390,958.

Specification of Letters Patent. Patented Sept. 13, 1921.

Application filed September 24, 1920. Serial No. 412,435.

To all whom it may concern:

Be it known that I, GEORGE J. HULBERT, a citizen of the United States, and residing at Seattle, in the county of King and State 5 of Washington, have invented certain new and useful Improvements in Adjustable Saws, of which the following is a specification.

This invention relates to improvements in 10 devices for adjusting saws and particularly for adjusting a plurality of circular saws as are used on edging machines.

An object of the invention is to provide 15 a device for adjusting the position of saws while rotating, the adjusting means being carried by the machine structure.

Another object of the device is to mount 20 the adjusting means in such a way that it will not come in contact with the work on the machine.

With these objects in view, the invention also comprehends other objects which are particularly pointed out in the following description and claims.

25 In the drawings:—

Figure 1 is a plan view of an edging machine with the improved adjusting means attached thereto.

Fig. 2 is a front elevation of the machine.

30 Fig. 3 is a sectional view on line 3—3 of Fig. 1.

Fig. 4 is a sectional view on line 4—4 of Fig. 3.

Fig. 5 is a detail section showing the 35 adjusting handle.

1 indicates the table of an ordinary type of edging machine, which is provided with bearings 2 for a slotted arbor 3, and a longitudinal groove 4 in the front edge thereof 40 of adapted to receive operating handles.

5 indicates the slot in the arbor 3, and said arbor has a plurality of saws 6 slidably mounted thereon, and provided with lugs 8 extending into the openings 7 in the saws, 45 and engaging in the slot 5 in the arbor to prevent rotation of the saw on the arbor. The arbor is also provided with a central bore 9, in which is mounted annularly slotted rings 10 provided with lugs 11 ex-

50 tending into slot 5 and having a bifurcated end portion to engage with the lugs 8 on the saws. Disks 12 are mounted in the slotted portion of the ring and are provided with a series of holes 13, spaced from the 55 center thereof, and eyes 14 on either side of the disks in the center portion. The

rings and saws are both adapted to rotate with the arbor, and to move longitudinally thereon, while the disks are held against rotation, but move in a longitudinal direction with the rings. Cables 15 are secured to the eyes of each disk and extend through the holes in the other disks beyond the end 60 end of the arbor where they are passed over a series of pulleys 16, and then are passed over pulleys 17 secured to the table of the machine. As shown, the cables extend in opposite directions from each side of the disks, passing over the pulleys 16 at opposite ends of the arbor and then extending 65 parallel to each other to the pulleys 17, after which they are brought toward each other and secured to eyes 19 on adjusting handles 18, which are slidably mounted in the groove 4 in the table of the machine. 70

Along the upper edge of the table is 75 formed a series of indentations 20 to provide a scale, so that the distance between the saws may be indicated thereon by the relative positions of the handles.

80 A pulley 21 is mounted near one end of the arbor, and adapted to receive a belt 22 through which the power for driving the saws is transmitted.

In the operation of an edging machine 85 with the above described saw adjusting devices, it will be obvious that the saws may be adjusted during the rotation thereof, simply by moving the handles in the slot 4 of the table, so that the handles indicate 90 on the scale, the desired distance between saws. In the movement of the handles, the cables 15 are moved therewith, and transmit the motion of the handles to the disks, which will be moved longitudinally in the 95 arbor, and through the rings will move the saws to the desired position.

What I claim is:—

1. In an edging machine, the combination 100 of a table, a slotted arbor rotatably mounted thereon, having a longitudinal bore formed therein, a plurality of saws slidably mounted on the arbor, and having lugs formed thereon, and extending into the slot in the arbor, a series of rings in the arbor having an annular groove therein, and a projecting lug 105 adapted to fit in the slot in the arbor and engage the lug on said saw, disks mounted in the rings, and means for moving the disks to space the saws a predetermined distance 110 apart.

2. An edging machine, comprising a table,

a slotted arbor rotatably mounted thereon, and formed with a longitudinal bore, a plurality of saws slidably mounted on the arbor, rings mounted in the bore, formed with lugs 5 adapted to engage the saws, and also formed with internal annular grooves, disks mounted in the grooves in said rings, and formed with holes, cables secured to said disks and extending from either side of each disk and 10 through the holes in the other disks beyond the end of said arbor, pulleys mounted on the table the edge of the table being formed with a groove and handles mounted in said groove the ends of said cables extending 15 around and passing over the pulleys and secured to the handles.

3. An edging machine comprising a table,

a slotted arbor rotatably mounted thereon and formed with a longitudinal bore, a plurality of saws slidably mounted on the arbor, 20 elements mounted in the bore, and connected with the saws, and means for moving the elements.

4. An edging machine comprising a table, a slotted arbor rotatably mounted thereon 25 formed with a longitudinal bore, a plurality of saws slidably mounted on said arbor, and means mounted within the bore and connected with the saws, and controlled from a remote point for moving the saws on the 50 arbor.

In testimony whereof I affix my signature.

GEORGE J. HULBERT.
